A. E. SPARROW

SUPPORTING FIXTURE

Filed March 25, 1927

INVENTOR

A. E. SPARROW
BY *Maurice Leo*.

ATTORNEYS

UNITED STATES PATENT OFFICE.

ARTHUR E. SPARROW, OF CHICAGO, ILLINOIS, ASSIGNOR OF ONE-HALF TO JAY C. CARTER, OF CHICAGO, ILLINOIS.

SUPPORTING FIXTURE.

Application filed March 25, 1927. Serial No. 178,273.

My invention relates to improvements in supporting fixtures, and it consists in the combinations, constructions, and arrangements herein described and claimed.

5 An object of my invention is to provide a supporting fixture which has novel means for holding day shades, night shades, curtains, drapes, valances, or the like.

10 A further object of my invention is to provide a device of the type described which may be rigidly held in place without the aid of screws, nails, or other fastening means.

15 A further object of my invention is to provide a device of the type described which has novel means for holding rigidly the various parts.

20 A further object of my invention is to provide a device of the type described which may be used as a clothes rod.

25 Other objects and advantages will appear in the following specification, and the novel features of the invention will be particularly pointed out in the appended claims.

My invention is illustrated in the accompanying drawings, forming part of this application, in which

Figure 1 is a front elevation of my device as applied to a window frame,

Figure 2 is an enlarged section along the line 2—2 of Figure 1.

Figure 3 is an enlarged section along the line 3—3 of Figure 1,

Figure 4 is an enlarged section along the line 4—4 of Figure 1, and

Figure 5 is an enlarged section along the line 5—5 of Figure 1:

In carrying out my invention, I provide an inner tubular member 1 having a plurality of aligned openings 2 therethrough.

10 Outer tubular casings 3 and 4 are slidably disposed upon the inner tubular member 1. The tubular casing 3 is provided with a plurality of grooves 5 which are equally spaced around the inner end thereof. A sleeve 6

5 having a plurality of equally spaced tongue portions 7 receivable in the grooves 5 is disposed concentric with the inner tubular member 1 and provided with external threads 8.

15 A nut 9 is disposed upon the sleeve 6 and adapted to be moved thereupon. U-shaped retaining members 10 and 11 are adapted to extend through the openings 2 for forming abutments for the sleeve 6 and the tubular casing 4.

Cup-shaped members 12 and 13 are pro-

vided with resilient integral neck portions 14 having aligned slots 15 cut therethrough. The neck portions 14 are receivable in the outer ends of the tubular casings 3 and 4 and resiliently held in place. Retaining 60 brackets 16 and 17 are provided with circular head portions 18 and 19, respectively. Central openings 20 are provided in the head portions 18 and 19 for receiving the neck portions 14 of the cup-shaped members 12 65 and 13. The head portion 18 of the bracket 16 is positioned between the cup-shaped member 12 and the adjacent end of the tubular casing 3. The head portion 19 of the bracket 17 is disposed between the cup-shaped member 13 and the adjacent end of the tubular casing 4. Openings 21 and 22 are provided in the bracket 17. The bracket 16 is provided with an elongated slot 23 and an elongated opening 24. The opening 21 70 of the bracket 17 and the slot 23 of the bracket 16 are adapted to receive the ends of a night shade, indicated generally at 25. The openings 22 and 24 are adapted to receive a curtain rod or the roller of a day shade, not shown.

The cup-shaped members 12 and 13 are provided with resilient walls 26 which taper inwardly. The walls 26 are provided with aligned slots 27 for receiving arms 28. The arms 28 are bent outwardly at 29 forming abutting portions 30 for a purpose herein-after described. The arms 28 are again bent at right angles at 31 and are provided with arcuate-shaped recesses 32 for receiving curtain rods 32'. Resilient friction pads 33 are forced for a portion of their width into the cup-shaped members 12 and 13 until they abut against the arms 28.

From the foregoing description of the 95 various parts of the device, the operation thereof may be readily understood. Let us assume that the various parts are assembled, as shown in Figure 1. In applying the device to a window frame, the device is disposed in the desired location with the U-shaped members 10 and 11 removed. The tubular casings 3 and 4 are then moved with respect to the tubular member 2 until the friction pads 33 are in engagement with the inner walls of the window frame indicated at 34. The U-shaped members 10 and 11 are then inserted into the openings adjacent the tubular casing 4 and the sleeve 6. The arms 28 are then moved so as to bring the abutting 100 105 110

portions 30 into engagement with the window frame. The nut 9 is then rotated upon the sleeve 6 and moved thereupon into engagement with the U-shaped retaining member 10. By continued rotation of the nut 9 upon the sleeve 6 toward the retaining member 10, the tubular casing 3, together with the sleeve 6, is forced in one direction, and the tubular member 10, together with the tubular casing 4, is forced in the opposite direction. In this manner, the friction pads 33 are forced against the inner walls 34 of the window frame. This force also frictionally holds the brackets 16 and 17 and the arms 28 against displacement due to the frictional contact between the adjacent members. The engagement of the arms 28 with the window frame aids in holding the device against displacement. The night shade 25, day shade or curtains, not shown, together with the curtain rods 32', may then be inserted in place.

It is obvious that by removing the brackets 16 and 17, together with the arms 28, the device may be readily positioned in a clothes closet, or the like, and serve as a clothes rod.

I claim:

1. A device of the type described comprising a tubular member having a plurality of aligned openings therein, tubular casings disposed upon each end of said tubular member, cup-shaped members having slots therein, resilient neck portions integral with said cup-shaped members and receivable in said tubular casings, retaining brackets dis-

posed concentric with said neck portions between said cup-shaped members and said tubular casings, arms disposed in the slots in said cup-shaped members, friction pads disposed in said cup-shaped members, means carried by said tubular member for forcing said tubular casings away from each other for rigidly securing said friction pads adjacent a support, said means comprising a sleeve having external threads disposed concentric with said tubular member, U-shaped retaining members disposed in the openings in said tubular member, and a nut mounted upon said sleeve and adapted to be moved into engagement with one of said U-shaped retaining members.

2. A device of the type described comprising a tubular member, tubular casings slidably disposed upon said tubular member, friction pads, means carried by said tubular casings for holding said friction pads, means carried by said tubular member for moving said tubular casings with respect to each other, said means comprising a sleeve disposed concentric with said tubular member, tongue portions integral with said sleeve, one of said tubular casings having grooves therein to receive said tongue portions, retaining members disposed in openings in said tubular member, and means disposed upon said sleeve and adapted to be moved into engagement with one of said retaining members.

ARTHUR E. SPARROW.
